UNITED STATES PATENT OFFICE.

ARTHUR V. BERRY AND ELMER S. BERRY, OF HEBRON, OHIO.

GEAR-SHIFT-LOCKING MECHANISM.

1,407,458.

Specification of Letters Patent. Patented Feb. 21, 1922.

Application filed June 27, 1921. Serial No. 480,515.

To all whom it may concern:

Be it known that we, ARTHUR V. BERRY and ELMER S. BERRY, citizens of the United States, residing at Hebron, in the county of 5 Licking and State of Ohio, have invented certain new and useful Improvements in Gear-Shift-Locking Mechanism, of which the following is a specification.

This invention relates to an improved 10 safety lever lock for gear shift mechanisms, and has for its primary object to provide a structure which will effectively serve to preclude the shifting of such levers when one of said levers occupies a position maintaining gearing governed thereby in intermeshed engagement with a gear train.

Another object of the invention resides 15 in providing safety locking mechanism of the character aforesaid upon farm tractors, and to combine the said mechanism with the driving and reverse gear controlling levers of a tractor, in order that one of said levers will be restrained from movement when the other cooperative lever occupies an active 20 position maintaining the gear controlled thereby in driving relation with the gear train of the tractor, the arrangement being such that it will be impossible for both the driving and reverse gears of the tractor to be 25 simultaneously locked in mesh with associated gearing, as may readily happen, and with disastrous results, when the locking mechanism is not employed.

For a further understanding of the invention, reference is to be had to the following 30 description, and to the accompanying drawing, wherein similar characters of reference denote like and corresponding parts throughout the several views thereof. In said drawing:

Figure 1 is a side elevation of a tractor, disclosing more particularly the drive gearing therefor and the manually operated levers for governing the operation of the 35 gearing.

Figure 2 is a vertical sectional view taken through the lever construction, and illustrating the locking mechanism, comprising the present invention, associated therewith.

Figure 3 is a transverse horizontal sectional view taken through the lever construction and the associated locking mechanism.

Referring more particularly to the 45 tails of the invention, the numeral 1 designates a farm tractor, which is formed to in-

clude a main horizontally extending frame 2 and a supplemental frame 3, which is slideable upon the main frame, the said supplemental frame being adapted to carry the power plant 4 of the tractor in the usual manner common to this particular type of tractor. A drive shaft 5 leading from the power plant is equipped with a spur pinion 6, which, upon movement on the part of the supplemental frame is designed to be moved into engagement with the teeth of a relatively enlarged intermediate gear 7. This latter gear is carried by a shaft 8, suitably journaled in connection with the main frame, and the shaft 8, in turn, is equipped with a spur pinion 9, which is constantly in mesh with an enlarged drive gear 10. This gear is adapted to be rigidly connected with the rear drive wheels, not shown, of the tractor, which are mounted upon the usual axles 11, projecting from fixed pedestals 12 carried by the under part of the main frame 2. By this construction, it will be apparent that when the frame 3 is shifted bodily, the pinion 6 will be moved into or out of meshing engagement with the intermediate gear 7, thus controlling the forward movement of the tractor.

Also arranged for cooperation with the intermediate gear 7 is the reverse gear 13 of the tractor. This gear is pivotally mounted as at 14 for swinging movement, and by being oscillated about the pivot 14, the said reverse gear is capable of being moved into or out of driving relation with respect to the intermediate gear, the said reverse gear being driven in any suitable manner from the engine or power plant 4. To govern the positions of the reverse gear, there is provided a bell crank 15, which is pivotally supported in any suitable manner from the main frame 2, and is also connected with an arm 16 extending to the axis of the gear 13, and a manually operated link 17 has its forward end pivotally connected with the bell crank, whereby upon movement on the part of the said link, the bell crank will be oscillated to throw the reverse gear into or out of meshing engagement with the intermediate gear 7.

To govern the selective actuation of both the forward drive pinion 6, and the reverse gear 13, the particular form of tractor disclosed employs a pair of operating levers 18 and 19, the former being utilized for the purpose of governing the positions of the

pinion 6 and the latter for governing the positions of the reverse gear. To effect the pivotal mounting of the levers 18 and 19, there is provided a bracket 20, which is fixed 5 to the frame 2, the said bracket being formed to include vertically disposed sides 21 which are provided with segmental upper surfaces 22, having notches 23 and 24 formed therein. The levers 18 and 19 are pivotally connected 10 as at 25 with the bracket 20, and beneath its pivot 25 the lever 18 is pivotally connected as at 26 with the slidable frame 3. It will be seen that by oscillating the lever 18, the supplemental frame may be longitudinally 15 adjusted to move its driving pinion or pinions 6 into or out of meshing engagement with the gear train. The lever 19 also has its lower end pivotally connected as at 27 with the link 17, so that by the oscillation of the lever 19, the operative positions 20 of the reverse gear with respect to the gear train may be readily governed. The said levers are maintained in their various operative positions by use of the ordinary spring 25 pressed latches 28, which are designed to be received within the notches 23 and 24 so that the levers may be locked in conjunction with the stationary bracket 20. It will be understood that the latches 28 have their 30 operation controlled by the ordinary lift levers 29, which are pivotally connected as at 30 to the upper ends of the levers 17 and 18 contiguous to the handles 31 thereof.

The construction so far described is that 35 commonly employed upon a well known make of farm tractor, and the present invention consists essentially in providing a safety lock mechanism for governing the operation of this mechanism. It will be manifest that by reason of the construction described, it is possible, either by carelessness or confusion on the part of the tractor operator, for both the reverse and drive gear to mesh with the intermediate gear 7 at 40 the same time, since there is nothing to prevent one lever from being operated when the other lever occupies a position maintaining its respective gear in mesh with the gear train. This accidental simultaneous meshing 45 of both the gears 6 and 13 with the intermediate gear frequently happens, because of the relationship between the levers 18 and 19, and naturally results in gear breakage, break downs and other unnecessary delay in the operation of the tractor. By 50 the present invention a locking mechanism is provided whereby it will be impossible to operate either one of the levers 18 and 19 when the other lever occupies a position 55 maintaining its respective gear in mesh with the intermediate gear.

This end is accomplished by the agency 60 of reversely positioned spring operated bolts 32. These bolts are mounted for sliding movement on a horizontal plane and are sup-

ported in conjunction with the side walls 21 of the bracket 20. Each bolt is formed to include an enlarged head 33, having a bevelled end 34, the latter being received within an elongated opening 35 provided in one of the sides 21. The opposite end of each bolt is provided with a reduced shank 36, which is also adapted to be received within an opening 37 formed in the opposite wall of the bracket, and a spring 38 surrounds each of the shanks 36 and is confined between the enlarged head 33 of each bolt and one of the side walls 21. Then, each of the levers 18 and 19 is provided with an opening 39, situated to register with the bolts 32 and 75 adapted for cooperation therewith. By this construction it will be obvious that when the levers 18 and 19 occupy the neutral positions, shown in Figure 1, the same may be 80 freely moved to their active positions without hindrance on the part of the bolt mechanism. This free movement of the levers can be effected because of the fact that the diameter of the openings 39 provided in said levers will not admit of the entrance of the 85 spring pressed bolt heads 33 therein, the said bolts being retained in retracted or inactive positions, with the reduced shank ends thereof projecting to a point where they will be out of engagement with the 90 levers proper. However, if, for example, the lever 18 is moved to an active position, throwing the spur pinion 6 in mesh with the intermediate gear 7, the said levers will 95 then be positioned side by side, which will 100 result in forcing one of the latch bolts longitudinally against the resistance by its spring 38, thus causing the reduced end of the said bolt to be forced into the opening 39 of the reverse lever 19 and thereby locking the 105 said reverse lever against movement during the retension of the lever 18 in its active position. It will thus be manifest that it will be impossible to move the reverse lever 110 from a neutral position when the lever 18 is in an active position. The relative arrangement of the lock bolts is such that the same operation will take place when the reverse lever is moved to assume an active position, in that the latch bolt governed 115 thereby will lock the lever 18 against movement. This construction provides a simple and positive structure for governing the operation of the throw levers, and effectively precludes any careless or accidental movements on the part of the levers that would 120 tend to simultaneously throw both the drive and reverse pinions in mesh with the intermediate gear. The construction therefore serves to prevent damage to the drive gear 125 ing of the tractor and eliminates expense, loss of time and general inconvenience that are naturally incident to said delays. The locking mechanism itself is of an extremely simple nature and may be readily applied 130

to a tractor of the type set forth without changing or altering the usual construction thereof.

What is claimed is:

- 5 1. A safety gear shift mechanism comprising a pair of pivotal levers, supporting walls arranged on opposite sides of said levers, a pivotal mounting for said levers, and a pair of reversely positioned spring pressed 10 bolts slidably carried by said walls, said bolts being formed to provide enlarged beveled ends and reduced shank ends, the said beveled ends being normally retained in the path of movement of said levers, whereby 15 the said bolts will be slidably projected when engaged by said levers, and each of said levers being provided with an opening capable of receiving reduced shank ends of said bolts when the latter are slidably projected by being engaged by said levers.
2. A safety locking mechanism for gear shift levers, the combination with a pair of pivotally mounted levers, of a fixed support arranged contiguous to said levers, and 25 spring actuated bolts carried by said support and capable of being engaged with said levers whereby when one of said levers occupies an active position, the other lever will be positively retained against movement 30 in an inactive position.
3. In locking mechanism for gear shift levers, the combination with a pair of pivotally mounted levers, of a fixed support arranged contiguous to said levers, said support being provided with openings capable 35 of aligning with cooperative openings provided in said levers, and reversely positioned spring operated bolts slidably carried by said support and arranged for cooperation 40 with said levers, whereby when one of said levers occupies an active position, the same

will force one of said bolts into the locking opening provided in the inactively positioned lever, thereby precluding movement on the part of said latter lever.

45

4. In a tractor, the combination with the gear shift levers thereof, of a locking mechanism for said levers, including a stationary support arranged contiguous to said lever, said support being provided with bearings 50 capable of aligning with openings provided in said levers, reversely positioned bolts arranged with sliding movement within said bearings and cooperative with said levers, said bolts being formed to include relatively 55 enlarged heads and reduced shanks, the openings and said levers corresponding substantially to the diameter of said shanks, and springs operating to normally project the enlarged heads of said bolts into the 60 path of movement of said levers.

60

5. In a tractor, the combination with the gear shift levers thereof, of a locking mechanism for said levers, including a fixed support arranged contiguous to said levers, said 70 support being formed to include bearings capable of being aligned with openings provided in said levers, each of said bolts being formed to include an enlarged head having a beveled end, and a reduced shank end, and a 75 spring operating to normally project the enlarged head of each bolt into the path of movement of said levers, whereby upon the oscillation of said levers, the heads of said bolts will be engaged to project the shank 80 ends thereof into locking engagement with the openings of said levers.

In testimony whereof we affix our signatures.

ARTHUR V. BERRY.
ELMER S. BERRY.
